UNITED STATES PATENT OFFICE

GUSTAV VON DEN STEINEN, OF CLEVELAND HEIGHTS, OHIO, ASSIGNOR TO THE GLASCOTE COMPANY, OF EUCLID, OHIO, A CORPORATION OF OHIO.

METHOD OF MAKING GLASS-COATED PIPE COILS

Original application filed December 14, 1928, Serial No. 326,027. Divided and this application filed November 10, 1930. Serial No. 494,511.

This invention relates generally to the application of vitreous or fused coatings to articles, and relates more particularly to a method for making pipe coils having such coatings.

This application is a division of my co-pending application Serial No. 326,027, filed December 14, 1928, in which is claimed apparatus and structure illustrated and described herein.

In coating a coil or other article with glass it is customary to apply the coating material in the form of a powder or spray, and then heat the article in a furnace to approximately 1800° F., at which temperature the powder is fused and converted into an impervious coating. At this temperature steel, and other available metals from which a pipe coil might be constructed, become so soft that it is a difficult problem to support the coil during the coating process so that it will retain its normal or intended shape and in such manner as to prevent the convolutions of the coil from sagging, warping, or being otherwise distorted. In addition to the problem of supporting the coil so as to prevent distortion thereof, the construction of a coil having a vitreous coating is further complicated by reason of the fact that the convolutions must not come in contact with the supporting means, or blemishes and imperfections will result in the coating at all such points of contact.

It is, therefore, an object of this invention to provide a novel method of making glass-coated pipe coils.

Another object of this invention is to provide a novel method of making glass-coated pipe coils in which the coil is suspended and held against distortion during the fusing of the coating material.

A further object of this invention is to provide a novel method of making glass-coated pipe coils which includes suspending a coil within a frame in such a manner as to prevent distortion of the coil and then heating the frame and the coil suspended therein to fuse the coating material.

Other objects and advantages of this invention will be apparent from the following

description taken in connection with the accompanying sheets of drawings, in which—

Fig. 1 is a plan view illustrating my method of making glass-coated coils.

Fig. 2 is a sectional view taken substantially on line 2—2 of Fig. 1.

Fig. 3 is a sectional view of a coil to be coated, taken on line 3—3 of Fig. 2.

Fig. 4 is a detail section, taken on line 4—4 of Fig. 2, illustrating the manner of holding and supporting the central column of a coil according to my method.

Fig. 5 is a detail elevation illustrating the manner of holding and supporting the convolutions of a coil according to my method.

Fig. 6 is a cross-section, taken on line 6—6 of Fig. 5, showing one of the coil supporting nipples, and

Fig. 7 is an elevation showing a plug for closing the supporting nipples of the end convolutions.

In the drawings, to which detailed reference will now be made, I have illustrated the manner of carrying out my method wherein a coil 10 to be glass-coated is supported and held within a framework 11 so as to prevent distortion of the coil or contact of the latter with the supporting means.

Before proceeding with a detailed description of the coil supporting means which I prefer to employ, it should be understood that my method may be advantageously used in making glass-coated pipe coils of various shapes and forms, but for purposes of illustration the coil in this instance is formed from two lengths of pipe bent to helical form, as indicated at 12 and 13, and arranged so that the convolutions of one helix alternate with the convolutions of the other helix, thus providing two separate paths of flow through the coil. To admit fluid to coil 10 I provide a central tubular column 14 extending coaxially with the coil and having the lower ends of helical coils 12 and 13 connected thereto adjacent its lower end at points 180° apart. The lower end of column 14 is closed, while at its upper end a threaded pipe nipple 15 is concentrically attached thereto, as by welding, to provide a suitable connection for a fluid supply line and also

to provide a substantially rigid connection for centrally supporting the coil during the coating process, as will be more fully disclosed hereinafter. The upper ends of helical coils 12 and 13 are connected at points 180° apart, as shown in Fig. 4, to a discharge fitting 16, which I prefer to construct in the form of a sleeve, arranged concentrically with column 14 and welded to the upper portion thereof. The diameter of the sleeve 16 is materially larger than the diameter of column 14 and of the supply pipe leading to column 14, so that the space 17, between sleeve 16 and the supply pipe, will serve as a discharge passage for coil 10. To facilitate the welding of the sleeve 16 to the column 14 the wall of the lower end portion 16' of the sleeve is flanged or bent inwardly to circumferentially engage the column 14, while at the opposite end of the sleeve 16 I provide an annular enlarged portion 18, by which the coil may be attached to the apparatus with which it is to be used, and to which a discharge connection may be conveniently applied.

For rigidly supporting the coil during the coating process I provide the framework 11, composed of members welded or otherwise securely fastened together to form a base portion 19, having uprights 20 upon which an annular member 21 is mounted. A cross-beam 22 extends diametrically across annular member 21 and carries a tubular projection 23 welded thereto from which coil 10 is suspended with its axis in alignment with the axis of the projection. Adjacent its free end projection 23 carries a removable pin 24 which extends diametrically through the walls of the projection. In order to support the coil at its center a piece of pipe 25 is connected to the nipple 15 of the column 14 as by means of a pipe coupling 26. When the upper end of pipe 25 is slipped over the projection 23 perforations provided in pipe 25 register with the perforations of the projection so as to admit the pin 24 which couples the parts together.

For supporting the coil about its perimeter I provide a carrier 26' which includes a flanged coil supporting member or ring 27 to which the coil is connected at spaced points about its perimeter. This supporting ring 27 is carried by a central hub 28 to which it is connected by bars 29 extending radially outwardly from the hub and having at their outer ends hooks 30 which engage the lower flange of ring 27 and are welded thereto. The hub 28 is of suitable diameter to permit it to be slipped over pipe 25 and is provided with aligned slots 31 which register with the perforations of pipe 25 and of projection 23 to receive pin 24 upon which the hub is supported. At the top of the coil as seen in Fig. 2, at points spaced about its perimeter, I provide internally threaded nipples

32 which are welded to the convolutions at one end of the coil. Supporting rods 33 are provided for connecting the coil to supporting ring 27 and have one end threaded and screwed into nipples 32. At their opposite ends rods 33 are welded to ring 27 and to the hooks 30 of bars 29. Notches are preferably cut in the lower flange of ring 27 to receive the rods 33 to permit them to be welded to the web of ring 27 along a portion of their length. 70

To make the coil a substantially rigid unit and to prevent sagging and distortion of its convolutions, spacers 34 are welded between adjacent convolutions and arranged in rows extending axially of the coil. The nipples 32 are arranged in alignment with the rows of spacers so that the convolutions are supported from the member 27 by the rods 33. The column 14, which extends substantially 80 coaxially of the coil, connects and supports the end convolutions thereof, and adds materially to the rigidity of the coil as a unit. 85

After the coil has been attached to the ring 27 and suspended from the frame 11, the coating material is applied to the entire surface of the coil including the spacers 34, the nipples 32 and the column 14. The supporting frame and the suspended coil are then heated, preferably by being placed in 90 a furnace which is brought to the temperature necessary to fuse the coating material. After cooling, the coil is removed from the frame by withdrawing pin 24 and is disconnected from supporting ring 27 by cutting 95 rods 33. The stub ends of rods 33 are unscrewed from nipples 32, and plugs 35 are then screwed into these nipples and sealed with litharge or other suitable material. 100

When the supporting frame and the coil are heated to the high temperature necessary to fuse the coating material, the metal of the supporting frame loses its rigidity and its members tend to buckle and twist out of shape. However, by my method of constructing and uniformly supporting the coil as a substantially rigid unit, the distortion and twisting of the members of the supporting frame can have no deleterious effect on the coil so long as the coil does not contact with the supporting frame. It will be seen that according to my method the coil is supported at its center and also at points around its perimeter so that each of the several convolutions of the coil is supported and rigidly held in properly spaced relation by the aligned spacers 34. The ring 27 of the carrier 26' is heavy and rigid and supports the coil evenly around its perimeter and prevents warping and distortion, while the column 14, connected to the projection 23, affords a central support and also tends to rigidly maintain the coil and the convolutions thereof in proper alignment. 110

Moreover it will be noted that according 130

to my method the coil and the carrier 26' are connected together at a plurality of points around the perimeter of the coil so that the carrier tends to prevent any lateral deflection 5 or swaying of the lower end of the coil relative to the axis thereof. The carrier in turn is connected at its center to the frame by a single connection which is on the axis of the coil so that when the frame members buckle 10 or twist any movement of the coil relative to the frame will in fact be movement of the coil as an entirety and of the coil and carrier as a unit, and will not be a movement of one portion of the coil relative to another portion 15 thereof.

While I have referred, in this specification and also in the claims, to a glass-coated coil, it will be understood that the invention is not limited to coatings that come within the 20 technical term "glass", and that I use the term "glass-coated" in the broader sense in which it means any vitreous or fused coating.

It is also to be understood that I do not 25 intend to limit my invention to the particular arrangements and steps of procedure herein shown and described, but regard my invention as including such changes as fall within the scope of the appended claims.

30 Having thus described my invention, I claim:

1. The method of making glass-coated pipe coils which comprises suspending a coil within a supporting frame so as to retain 35 its normal shape, applying coating material to the external surface of said coil, and then heating said coil and supporting frame to the temperature required to fuse said material.

2. The method of making glass-coated 40 pipe coils which comprises supporting a coil centrally thereof and also at spaced points about its perimeter, applying coating material to the external surface of said coil, and then heating the coated coil while thus supported to the temperature required to fuse 45 said material.

3. The method of making glass-coated pipe coils which comprises attaching a coil to a supporting structure at a plurality of 50 points whereby said coil is uniformly supported and held against distortion from its normal shape, applying coating material to the external surface of said coil, and then heating said coil to the temperature required 55 to fuse said material.

4. The method of making glass-coated pipe coils which comprises attaching a carrier to one end of a coil, connecting the carrier with a supporting structure with the 60 axis of the coil substantially in alignment with such connection, applying coating material to the surface of the coil, and then heating the coil to fuse said material.

5. The method of making glass-coated 65 pipe coils which comprises forming a coil

having convolutions and spacers between adjacent convolutions, attaching a carrier to said coil at points aligned with said spacers, suspending said carrier and coil in a supporting frame, applying coating material to 70 said convolutions and spacers, and then heating said coil while thus supported to fuse said material.

6. The method of making glass-coated pipe coils which comprises attaching a coil to 75 a carrier at a plurality of points spaced around the perimeter of the coil, suspending the carrier in a supporting frame by attaching the carrier to the frame at a single point in alignment with the axis of the coil, applying coating material to the coil, and then heating the coil and frame assembly to fuse the coating material.

In testimony whereof, I hereunto affix my 80 signature.

GUSTAV VON DEN STEINEN.
